WOOD GRAINING MACHINE

Arthur I. Baldwin, Oakland, Calif.

Application March 15, 1935, Serial No. 11,315

2 Claims. (Cl. 144—115)

This invention is a wood graining machine and is directed to a machine for removing the summer wood while leaving the winter wood so as to cause the wood to appear weathered and setting 5 the grain in relief.

In finishing a piece of lumber in the ordinary manner such as planing and sanding, the grain is only apparent due to the difference in density between the summer and winter wood or to the 10 difference in color or shade therebetween.

This invention contemplates the removal of a portion of the summer wood, leaving the winter wood intact whereby the winter wood sets out in bold relief and which may be accentuated by tinting with different colors from various angles if desired, providing very artistic effects especially 15 where burls are treated by my process.

The main object of the invention, therefore, is to provide a machine which will remove the summer 20 wood to any desired depth while leaving the winter wood intact, thereby presenting the grain of the wood in relief.

Another object of the invention is to provide a machine of the class described with which definite 25 longitudinal bands of relieved grain may be formed in the board or by which broad panels may be relieved throughout their entire surface.

A further object of the invention is to provide 30 a machine as outlined with adjusting means whereby the depth of relief may be governed, the machine being adjustable to compensate for wear in the cutting elements as also for gauging the depth of the cut.

Other objects and advantages of the invention 35 will become apparent as the following description is read on the drawings forming a part of this specification and in which similar reference characters are used to designate similar parts through the several views, of which:

40 Fig. 1 is an end elevation of the machine.
Fig. 2 is a front elevation.

Fig. 3 is a top plan view showing a board passing through the machine.

Fig. 4 is a rear elevation of the machine.
45 Fig. 5 is an end view of a board indicating the work done by the machine.

The invention consists of a frame 10 having mounted thereon a plurality of driven rolls 11 rotatably mounted in bearings 12, forming a support for the boards or panels while being relieved.

50 Adjustably mounted in nuts 36 secured to one side of the frame 10, are vertically disposed screw shafts 37, each provided with a beveled pinion 38, meshing with a similar pinion 39, on shaft

40, which is rotatably mounted in a head 13. A hand wheel 41 is provided for rotating said shaft 40, so as to effect simultaneous rotation of the screw shafts 37 in either direction. Each screw shaft 37 is provided with a grooved collar 37^a 5 which is engaged by an angular portion of a bracket 13^a, depending from said head, so that the head is caused to be raised or lowered by rotation of the shaft 37.

Mounted in bearings 14 carried by said head is 10 a brush carrying shaft 15, which shaft is driven by a suitable motor 16 and on which shaft, brushes 17—18 are suitably secured, the brushes being driven preferably at motor speed.

The brushes are formed of a multiplicity of substantially fine tempered steel wires, the usual 15 spring steel or piano wire being preferable so that the ends may retain their edges.

The rollers 11 are driven at a comparatively low speed by suitable belting or gearing as is indicated in the drawings, a pulley or sprocket being provided on the shaft 15 which drives through the belt 19 to a large pulley 20, second reduction being obtained between the pulleys 21 and 22, the 20 rolls 11 being driven from shaft 23 through pulleys 24 and 25, the pulleys all being driven in the same 25 direction and at the same speed.

Idle rollers 26 are suitably spaced at the discharge end of the machine and an adjustable idle roller 27 is mounted in links 28 which are adjustable through links 29 and lever 30 by means of the hand lever 31, the roller being urged by spring 32. This idle roller is only needed under certain conditions, the machine operating just as 30 efficiently with certain kinds of wood without the use of this roller while with certain kinds of wood the idle roller is required to prevent the brush from dragging the wood through the machine too quickly.

The head 13 is indicated as being slidably 40 mounted in pipes 33 which are secured to the frame 10 as indicated at 34, the head having standards formed of pipe sections 35 which are slidably in the pipe 33. It will be noted that the head 13 is of a cantilever type of construction, and the arrangement of the telescoping members with respect to the screws 37 is such that said members relieve the screws of the strain imposed by the weight of the overhanging head and mechanism thereby, so that the screws may be rotated without binding.

Fixedly secured to the frame 10 are nuts 36 in which are threadedly mounted the adjusting screws 37 which are operated coincidentally by means of bevel gears 38 and 39 which bevel gears 50 55

39 are mounted on a shaft 40, which shaft is provided with a hand wheel 41 whereby the head may be adjusted to suit the depth of graining and the thickness of the board being grained.

5 In Figs. 1 and 3, the operation of the machine is clearly disclosed, the board 42 being acted on by the brush 17, the end 43 of which clearly indicates the grain of the wood set in relief by cutting out the summer wood, Fig. 5 clearly indicating the result of the operation in which the ridges 44 indicate the winter wood and the relieved portions 45 indicate where the summer wood has been cut away between the rings of winter wood. It will be noted that to increase the depth of the relief 45, it is but necessary to adjust the brush 17 to a lower position, by adjusting the head 13 through the medium of the hand wheel 41.

10 The operation of the machine is as follows: 20 With the motor 16 operating at full speed, the board is fed under the brush 17 which has been adjusted to a point where it definitely engages the board, by means of the hand wheel 41 which is used to lower or raise the head 13 as may be 25 required.

15 The brush 17 being formed of thin wire, creates but little friction on the board while the rollers 11 feed the board through the machine at a low rate of speed, the brush cutting away 30 the summer wood and leaving the winter wood in relief. Where additional friction is required to drive the board, the roll 27 is adjusted into operative position as is shown in Fig. 2.

35 Where wide panels are to be grained, one edge of the panel may first be grained with the other edge extending out through the gap 46 and after its passage therethrough, the panel may be reversed and passed through the machine a second time.

40 In the event that the depth of relief is not as deep as desired in the first passage through the machine, the board may be passed through the machine a second time to increase this depth without in any way changing the result other 45 than to increase the relief.

Having described an operative machine for forming the grain of wood in relief, it will be noted that variations in construction and arrangement which are consistent with the appended claims may be resorted to without detracting from the spirit or scope of the invention or sacrificing any of the advantages thereof. 5

I claim:

1. A wood graining machine comprising a frame, a plurality of rollers rotatably mounted in said frame and arranged transversely of the latter, rotatably spaced screw shafts adjustably engaging said frame, a head having brackets at one end through which said screw shafts extend, means preventing movement of the brackets axially of the screw shafts, said head and said frame having complementary guide members located at one side of the frame adjacent to said screw shafts and so relatively constructed and arranged with respect to the screw shafts as to prevent binding of the brackets during rotations of said shafts, said head being extended laterally over the frame and rollers with its outer end free, a brush rotatably supported by said head, and means for rotating said screw shafts so as to raise and lower said head with respect to the frame. 20

2. A wood graining machine comprising a frame, a plurality of transversely arranged aligned rollers mounted in said frame, tubular guide members secured to one side of the frame, rotatably spaced screw shafts adjustably engaging said frame adjacent to said tubular guide members, a head having brackets at one end through which said screw shafts extend, said head extending laterally over the frame and rollers and having its other end free, means carried by said screw shafts for preventing axial movements of the brackets with respect to said shafts, rods secured to said head and telescoping within said tubular 25 guide members, a brush rotatably supported by said head, and means for simultaneously rotating said screw shafts so as to raise and lower the head with respect to the plane of said rollers. 30
